United States Patent Office.

W. C. WENDELL, OF ALBANY, NEW YORK.

Letters Patent No. 88,684, dated April 6, 1869.

IMPROVEMENT IN BOOK-COVERS.

The Schedule referred to in these Letters Patent and making part of the same.

To all whom it may concern:

Be it known that I, W. C. WENDELL, of the city of Albany, and county of Albany, in the State of New York, have invented a new and improved Book-Cover; and I do hereby declare that the following is a full, clear, and exact description thereof, reference being had to the accompanying drawings, making a part of this specification, in which—

Figure 1 is a perspective view of a bound book, which is provided with my improved cover.

Figure 2 shows the manner of making the cover.

Figure 3 is a sectional view, showing the manner of making the flexible back to the cover.

Similar letters of reference indicate corresponding parts in the several figures.

This invention relates to a new and improved cover, which is designed for protecting bound books, which are subjected to considerable wear and tear, such, for instance, as school-books belonging to circulating libraries, and books that are very highly and expensive bound, which it is desired to preserve from injury for a long time.

The invention is designed to furnish the trade with book-covers of different sizes, shapes, and styles, adapted for the various sizes and shapes of bound volumes, which covers shall be so made as to allow of their ready application to or removal from books, without the use of cement, stitching, or other fastening; and which covers are also so made that they will fit snugly upon books for which they are made, and allow them to be opened and shut with perfect freedom, without possessing that unpleasant looseness which is usually found in using books, whose covers have been manufactured upon them.

The nature of my invention consists in a book-cover, which is adapted to envelop the bound covering of a book, and protect it from wear, and from becoming soiled through use, and which is produced of paper, so cut, folded, and secured as to form two pockets for receiving and covering the side-boards of a book, which pockets are connected together by a flexible strengthened back, for covering and protecting the back of the book, the whole being so made as to be readily slipped upon or removed from a book-cover, as will be herein-after explained.

To enable others skilled in the art to understand my invention, I will describe its construction and operation.

In the accompanying drawings—

A A represent those portions of the covering which enclose the side-boards of a book, and

B represents the connecting portion of the cover which encloses the back part of the book.

The cover is cut out from one piece of paper, as represented in fig. 2, with the three folding flaps, a a', on each side portion, or on each side of the central or back portion B, as indicated by the dotted lines in the figure last referred to.

Before folding the flaps a a', narrow pieces c c' of cloth or leather, are neatly pasted on opposite sides of the connecting back portion B, for the purpose of strengthening this portion, preventing it from readily tearing, and affording it durability, without impairing its flexibility.

If it is desired to render the corners of the book-cover more durable than would be afforded by the material of which the cover is chiefly composed, pieces of cloth or leather may be pasted upon the cover at proper points to protect the said corners.

The flaps a a' are then folded, lapped, and pasted, and the flaps a' a' folded over them and pasted down securely, thus forming two pockets, ready to receive the covering boards, or lids of a book, as represented in fig. 2.

This cover is applied to a book by turning both lids, or covering-boards backward, and then drawing both pockets of the cover over the lids at the same time. When the back B of the cover is brought against the back of the book, the lids can then be closed, and the cover, if properly cut, will fit snugly, and be held in place without any other fastening or manipulation.

The cover can be removed from the book with the same facility as it was put upon it, by again turning back the lids and drawing the cover off.

Having described my invention,

What I claim as new, and desire to secure by Letters Patent, is—

As an improved new article of manufacture, the within-described book-cover, made of one piece of paper, shaped, folded, and stayed with cloth or leather strips c c', all in the manner shown and described.

W. C. WENDELL.
